COSMETIC PENCIL

Walter B. Spatz, Los Angeles, Calif.

Application January 9, 1956, Serial No. 39,647

Term of patent 14 years

(Cl. D86—10)

Figure 2 is a side elevation of the barrel of the cosmetic pencil of Figure 1, with the cap removed, the dotted lines representing a marking crayon for the purpose of illustration;

I claim:

The ornamental design for a cosmetic pencil, as shown and described.
